UNITED STATES PATENT OFFICE.

ALMER M. McAFFEE, OF BAYONNE, NEW JERSEY, ASSIGNOR TO GULF REFINING COMPANY, OF PITTSBURGH, PENNSYLVANIA, A CORPORATION OF TEXAS.

PROCESS OF CONVERTING OILS.

1,424,574.

Specification of Letters Patent. Patented Aug. 1, 1922.

Application filed September 30, 1918. Serial No. 792,615.

To all whom it may concern:

Be it known that I, ALMER McDUFFIE McAFFEE, a citizen of the United States, residing at Bayonne, in the county of Hudson and State of New Jersey, have invented certain new and useful Improvements in Processes of Converting Oils, of which the following is a specification.

This invention relates to processes of converting oils; and it comprises a method of obtaining a substantially complete conversion of high boiling petroleum oils into high grade low boiling products of the nature of gasoline, solvent oils, and kerosene, or of gasoline to the exclusion of other products, and in general of cleanly and completely converting higher boiling petroleum oils into lower boiling oils, wherein a liquid body of such a high boiling oil is subjected to a long- continued heat at a temperature below "cracking temperatures" but sufficient to cause boiling or ebullition in the presence of aluminum chlorid, the low boiling products formed being abstracted from said liquid body as fast as produced and proportionate quantities of fresh oil being advantageously added to such body to maintain its volume, (and thereby the concentration of the aluminum chlorid) constant; all as more fully 30 hereinafter set forth and as claimed.

Crude petroleum always contains high boiling and low boiling constituents in varying proportions. As these low boiling constituents are worth more than the high boiling constituents, the effort in any distillation is to increase the amount of low boiling oils yielded; to increase the amount of gasoline and burning oil. This is ordinarily done by conducting some portion of the distilling 40 operation in such a manner as to effect a destructive distillation or cracking of the high boiling oils. This yields more gasoline but of a lower grade. The naturally contained low boiling constituents of petroleum such as gasoline, are mostly saturated compounds which need little "treatment" to render them of commercial grade while the low boiling products obtained by this cracking operation are unsaturated and of low 50 grade being foul smelling, tending to burn with production of smoke, soot, etc. The market value of low boiling oils however is now so high that cracking of the high boiling residual oil is pushed as far as possible, 55 high heat and pressure being resorted to for

this purpose. At temperatures around 650° F. and above, a considerable proportion of the oil, but not all, can be cracked down to yield low boiling bodies without such a far-going destruction of the hydrocarbon molecules as to yield undue proportions of gas, tar and coke. The yield of these cracked gasolines and kerosenes does not usually exceed 10 to 20 per cent and the greater proportion of the high boiling oils treated remains as residual low grade material.

In the present invention I have devised an economical and ready method of converting high boiling oils into low boiling products with a conversion which is, in contradistinction to the usual cracking methods, substantially complete, 80 to 85 per cent of my original oil reappearing in the form of a water white, sweet, low-boiling oil of substantially saturated character needing little or no refining with acid and being susceptible of direct marketing.

To this end I avail myself of aluminum chlorid as a catalytic agent for converting, or depolymerizing, the high boiling oils into low boiling products such as gasoline. As is well known, aluminum chlorid exerts vigorous actions upon many organic bodies; a fact which forms the basis of the ordinary "Friedel & Crafts reaction," which is much used in laboratory practice, and particularly for synthesizing aromatic hydrocarbons of higher molecular weight from hydrocarbons of lower molecular weight with the aid of organic chlorids. Its use in the petroleum art has been attempted for various purposes but, owing to the lack of certain necessary conditions and precautions, without success. As stated, the action of aluminum chlorid on organic bodies is vigorous, and without a careful regulation of conditions, this action is apt to produce very irregular results. And the products which it makes in these actions it is very apt to destroy again, or convert into other bodies. The action is one tending to go forward to an equilibrium or balance. Without careful control of conditions, aluminum chlorid has a marked tendency to produce resins and tar. For these reasons in these prior attempts in treating petroleum the result was that while some light oils were produced, there was a large production of gas and heavy oils; instead of the reaction going on solely to the production of light oils, as is desirable for the present purposes,

it gave large proportions of undesirable by-products.

I have found that by suitable regulation of conditions and the observance of a number of 5 precautions, the reaction of aluminum chlorid on the high boiling oils may be made regular and controlled; and be used to effect a clean and complete conversion of such higher boiling oils into lower boiling oils 10 with the production of substantially no tarry or resinous bodies or byproducts of low commercial grade; and in particular that I can use it to produce a substantially complete conversion into gasoline of all higher boiling 15 oils. The products are saturated compounds and have little or no power of absorbing iodin, a common test in this respect.

In this operation there should be maintained a substantially uniform concentration 20 of the aluminum chlorid used in the body of oil under treatment, while the low boiling products formed by its catalytic action must be removed from its sphere of influence as fast as formed to prevent retrogressive 25 changes. To maintain the concentration of aluminum chlorid at a constant point the volume of oil under treatment should be replenished with new or fresh oil as fast as the low boiling materials formed are removed from it; the amount of addition corresponding to the volume of low boiling products removed. Furthermore, the concentration of the aluminum chlorid must be substantially uniform and constant throughout 35 the whole body of oil and as ebullition and diffusion cannot be relied upon to preserve this uniformity, and particularly since aluminum chlorid tends to concentrate in or on insoluble coky bodies produced, the whole 40 mass must be kept in vigorous agitation throughout the process. With ordinary rotary stirrers a speed sufficient to keep the bottom of the apparatus clear of any sediment should be maintained. This agitation 45 is a fundamental necessity for uniform results. Further, as aluminum chlorid is a rather volatile body and begins to volatilize freely at temperatures above 365° F., the temperature of the vapors at the point of 50 exit from the system should not rise above 350° F. With the vapor exit temperatures at or below 350°, the vapors of high boiling oil which tend to form, are condensed and returned and with them is returned any 55 aluminum chlorid which may vaporize. This is not only useful in maintaining the concentration of aluminum chlorid in the body of oil constant but has the further advantage that the condensing apparatus 60 for the gasoline, etc. beyond the still is kept clear and free and does not plug up. Aluminum chlorid tends to form compounds (hydrocarbon addition products of aluminum chlorid or double compound of hydro- 65 carbon and aluminum chlorid) with the

hydrocarbons which, like aluminum chlorid itself, are volatile, and if these compounds are allowed to pass forward stoppage of the condensers is apt to occur. The temperature of the mixture of oil and aluminum chlorid 70 should be higher than the end boiling point of the low boiling oil produced. The particular temperature which is desirable in the oil mass will vary with the particular constitution of the petroleum oil being treated, 75 but, as a general rule, the temperature will not rise much above 500 F. even in the case of very high boiling oils. A temperature of 500 F. in the body of oil is quite suitable for most high boiling oils. At 500 F. gas 80 oil, lubricating oil and most residual petroleum oils will in admixture with aluminum chlorid begin to boil vigorously in the present process. This boiling is incidental to the progress of the reaction and is also 85 useful in maintaining homogeneity of the body of oil and reagent. The lower the end boiling point of the higher boiling oil operated upon, the lower is the temperature necessary for conversion. The reaction 90 takes place at temperatures below the end boiling point of the higher boiling oil used. In general I find it best to operate between 500 and 600°, oil temperatures, as extremes. In the reaction of aluminum 95 chlorid with these high boiling residual oils and distillates, in the production of gasoline, boiling and the formation of gasoline are vigorous between 500 F. and 600 F., a substantial amount of boiling, with the class 100 of oils here contemplated, setting in above 470 F. At 500 F. with high boiling oils the gasoline forming reaction is not so fast as to be uncontrollable; it does not tend to become violent or to form undesirable byproducts; 105 and particularly where the low boiling bodies formed are removed from the sphere of reaction as fast as produced. This removal of the low boiling bodies from the influence of the aluminum chlorid substantially as fast as they are produced is 110 advantageous. If allowed to remain in the presence of aluminum chlorid, the low boiling bodies may be resynthesized to high boiling bodies or they may be broken down into 115 gas.

The oils and the apparatus used should be free of water or moisture and of air or dissolved oxygen. Both moisture and oxygen lead to the production of undesired side reactions, apart from the undesirable action of the moisture on the aluminum chlorid itself. For this reason, in treating crude petroleum it should be submitted to a period of preliminary distillation or heating, not only to get rid of the low boiling constituents naturally present but also to free the still and the oil of moisture. Where a high boiling residual oil is used, or a distillate, and it is transferred from another still 120 125 130

while hot, this preliminary heating or distillation is not necessary; but if the high boiling oil used has been exposed to air or has been in storage, it is commonly better to 5 heat it for some time prior to adding the aluminum chlorid. For the same reason the oil used in replenishing the body of oil under treatment is fed in hot or dry. A test of the desirable high degree of freedom 10 from moisture of the apparatus and its contents is the absence of hydrochloric acid gas from the distillate. With dry aluminum chlorid, dry oil and dry apparatus, the distillates will be free of hydrochloric acid. 15 Under such circumstances, hydrochloric acid is only formed where, as is later described, a little chlorin is fed into the still during the operation.

The present process may be used on any 20 crude petroleum or on any high boiling residual oil, such as fuel oil, still bottoms, etc. High boiling distillates like gas oil and lubricating oil may be treated by the present process to make low boiling products.

25 The time of operation is a very important factor. If the heating be forced so as to give a rapid distillation, not only are high boiling bodies sent over with the low boiling, and aluminum chlorid or its compounds volatilized, but sufficient time is not given for 30 the action of the catalytic agent on the body of liquid oil under treatment.

The aluminum chlorid employed may be 35 any commercial preparation but should be anhydrous. Any moisture present decreases the amount of effective aluminum chlorid to that extent. The aluminum chlorid may be formed from hydrochloric acid or chlorin passed over metallic aluminum, or from 40 chlorin passed over a mixture of alumina, such as bauxite, with carbon. The aluminum chlorid thus produced may be condensed and directly added to the still. Or the vapors of aluminum chlorid may be led directly 45 into the still. The aluminum chlorid used may be mixed with or dissolved in the inflowing oil. At the end of the operation of converting the oil, as hereinafter described, the residual coke and aluminum chlorid form a 50 black granular mass and this may be used as a source of aluminum chlorid for the reaction; the granular mass for this purpose being heated in any suitable vessel and a small amount of chlorin passed over it. In 55 the presence of this gaseous chlorin, aluminum chlorid volatilizes freely while in its absence it is hard to remove the aluminum chlorid from the granular coke mass. The aluminum chlorid may however be recovered 60 in other ways.

Some of the results of my invention may be obtained from the use of ferric chlorid and zinc chlorid; but they are not so active as the aluminum chlorid and are not as well 65 adapted for the present purposes; the for-

mation of low boiling oils from high boiling oils.

Any suitable type of apparatus may be employed for the present purposes. An ordinary "cheese box" type of still, provided with a vapor conduit having means for cooling by air or otherwise at one place and means for returning heavy oil vapors condensed therein to the body of oil in the still, may be used. The apparatus should 70 be provided with an efficient stirring mechanism and with means for adding fresh oil and catalyst from time to time or continuously.

In the accompanying illustration I have 75 shown, mainly in vertical section and more or less diagrammatically, an apparatus of a type suitable for carrying out the described process.

In this showing, element 1 designates as a 80 whole a still which may be of iron or steel or other suitable material. Within this still is mounted a stirring and agitating apparatus consisting of a revoluble shaft 2 carrying at its base a chain drag or other form of 85 agitating device 3. It may be actuated by pinion 4, driven from shaft 5. Near the base of the still is an outlet 6 which may be used for withdrawing fluid oil. The man-hole 7 may be used for cleaning and with- 90 drawing coky residues. The inlet 8 may be used for supplying oil. The manhole 9 may be used for supplying aluminum chlorid, etc. The furnace 10 may be used for supplying heat. Connected with the upper part of the 100 still is conduit 11 leading to an air cooled condensing chamber or back trap 12 for the purpose of returning condensates of high boiling vapors. Beyond this condens- 105 ing chamber the conduit 13 leads to another air cooled condensing chamber 14. At its base this chamber is provided with an outlet 15 communicating with a reflux conduit 16. Above uncondensed vapors are led for- 110 ward through 17 communicating with another air cooled condensing chamber 18. This air cooled condensing chamber 18 at its base has an outlet 19 leading back to the reflux device. Depression 20 in this line acts as an oil trap. Returning to the last named air 115 cooled condensing chamber, vapors are led from it through conduit 21 past thermome- 120 ter 22. These vapors pass into and through cooled condenser 23 cooled in any suitable way as immersion in water in tank 24.

The operation of this device is evident from the foregoing. The still 1 is charged with a suitable quantity of oil and aluminum chlorid and distillation begun. High boiling oils and vapors are condensed and 125 returned by the several air-cooled condensing means described. Distillation may be conducted at any rate desired and the temperature of the boiling mass of oil and aluminum chlorid will be that at which it 130

will boil under atmospheric pressure, say, around 500° F. in the case of high boiling petroleum oils. The important point in conducting the operation is the temperature marked by thermometer 22. The temperature as shown by the thermometer at this point should not rise above 350° F. If the thermometer remains at about 350° F., the vapors condensing in the condenser 23 will be gasoline and kerosene, which may be afterwards redistilled and separated. With a somewhat lower thermometer temperature at the point of exit of vapors from the distilling system, say, about 300° F., the distillate will all be good, clean commercial gasoline of a saturated character.

A suitable proportion of aluminum chlorid for the purposes of the present process is about 2 to 5 per cent of the body of oil under treatment. With large amounts of oil under treatment in a still, about 5 per cent is a good proportion. This proportion is relative to the amount of oil temporarily in the still and not to the whole amount of oil treated by a given amount of chlorid. Considering the amount of oil treated, in obtaining complete conversion with 5 per cent in the still, one part of aluminum chlorid will treat about 50 parts of oil before losing high activity. With a less complete conversion it will of course treat much more. Much depends on the character of the particular oil treated.

By feeding a little chlorin into the still during the operation the period of activity of the aluminum chlorid is considerably enhanced.

In the treatment of oil by the described process, it is found that a single charge of aluminum chlorid may be used for two or three days continuously before losing its high activity. At about the end of the first day after the addition of a new charge of aluminum chlorid, the contents of the still exhibit a peculiar phenomenon. The viscosity of the charge in the still increases, comparatively suddenly, until the contents are so gummy and viscous that the rotation of the stirrer is attended with considerable difficulty. At this time more power should be applied and the stirrer forced to continue in rotation. In the course of an hour or so the high viscosity begins to disappear and the rotation of the stirrer once more becomes free. If the stirring is kept up continuously as described the activity of the aluminum chlorid continues substantially undisturbed throughout these changes. In about another day the aluminum chlorid begins to accumulate in coky granules which tend to settle out if the stirring is discontinued. The aluminum chlorid in these granules for a time preserves its activity but this gradually decreases. When these granules lose high activity as evinced by an un-

due lessening of the flow of gasoline, etc., from the condensers, the granular residue should be removed and a fresh charge of aluminum chlorid placed in the still. Or the whole contents of the still may be dumped, the granules allowed to settle out and the oil replaced in the still. Or a fresh charge of aluminum chlorid may be added to the mass in the still and the operation continued without removing the first or exhausted charge, and this may be continued until there is too much of an accumulation of coky material in the still.

The still may be provided with any suitable means for trapping and withdrawing this granular residue and the granules removed continuously or from time to time, fresh aluminum chlorid being added to the contents of the still to correspond to the amount withdrawn with the granular material, the addition being in any of the ways previously described.

The time factor in this reaction I regard as of high importance. Any given petroleum oil or product is a complex of very many different hydrocarbons, many of which differ materially in their reaction with aluminum chlorid and their speed of reaction therewith. In the described operation, any portions of the oil which are slowly or difficultly reactive with aluminum chlorid are simply held in the still until the desired reaction takes place; when the products are at once removed. Those portions of the oil in the still, and of the oil fed to the still, which are quickly converted are of course as quickly removed from the sphere of reaction. Other portions more slowly reactive remain in the presence of the aluminum chlorid until the desired reaction takes place.

In operating upon the ordinary types of crude oils, residual oils, etc., I have found it a desirable speed of operation to distil in such a way that a distillate equivalent to about one-third of the volume in the still is formed every four hours; or, stated in another way, so that the distillate per hour amounts to about 10 to 12 per cent of the volume maintained in the still. This volume is of course maintained constant by the influx of fresh oil. Operating in this manner difficultly convertible portions of the oil may remain in the still under the influence of the aluminum chlorid for two or three days. Heating, distillation and other conditions should be so controlled as to spread the period of high activity of a charge of chlorid over at least 48 hours.

In the practical operation of the described process, I have obtained as high as 85 per cent conversion of a high boiling oil into a low boiling oil. In normal operation perhaps 10 per cent of the oil is converted into gas and 5 per cent forms coke. The gas may be used in heating the still. There ap-

pears to be no formation of tar or resin and the residual granular coke containing the aluminum chlorid appears to be a clean product.

5 In operating in the manner described the distillate is free of chlorin and of aluminum chlorid. Where a current of chlorin is introduced, some hydrochloric acid is produced but this goes over with the vapors without 10 uniting therewith and may be readily separated from the condensed oils. Unlike cracked gasoline and kerosene, the distillate is composed apparently wholly of saturated compounds and suffers but little loss on refining or treatment with sulfuric acid. It 15 gives little or no reaction with iodin. It is generally of such a character where the operation is conducted as described, as to require no refining and it may be sent directly into 20 the market without chemical treatment. If desired it may be given an alkali wash and particularly where free chlorin has been led into the still. The product coming from the still in the described operation, where the 25 vapor is led off at about 350° is what is known in petroleum refineries as "naphtha" and may be condensed as a whole or fractionated to give gasoline, "solvents", (the grade of distillate marketed for use in varnish and the like as a substitute for turpentine and sometimes known as "turpentine substitute") and kerosene. The kerosene and solvents fractions may then be again treated 30 with aluminum chlorid to afford gasoline. 35 Conversion of these fractions into gasoline is much quicker than that of the heavy oil originally treated. Or the gasoline, solvents and kerosene (illuminating oil) may be condensed separately in the usual manner from 40 the vapors coming from the still. The kerosene fraction is good water-white oil, ascending the wick readily and burning with a clean flame. Kerosene and solvent fractions and the like from ordinary distillation may 45 be treated with the aluminum chlorid. The reaction occurs at lower temperatures when such distillates are treated than when higher boiling distillates, such as gas oil or the like, are treated. 50 By adjusting the temperatures at the exit from the still to the condenser at various degrees of course the main body of the distillate may be made of different character. By maintaining the temperature at the exit 55 of the vapor at about 350, the main body of the distillate is gasoline. If the temperature of the vapors leaving the distilling system is lower, being at, say, about 300 F., the kerosene and solvents fractions are eliminated and the product of the vapors upon 60 condensation is directly marketable as gasoline. By dropping the exit vapor temperatures the kerosene and solvents fraction reflux to the still and are again exposed to the 65 action of the chlorid.

The present process is applicable to sulfur-containing oils without previous purification as under the catalytic influence of the aluminum chlorid most or all of the sulfur is split off harmlessly as sulfuretted hydrogen, but in oils where the amount of sulfur bodies occurring is high it is better to give the oil, to be converted into gasoline, a previous treatment with sulfuric acid to remove some of these sulfur bearing compounds and thereby prolong the period of activity of aluminum chlorid. This acid treatment will also remove moisture.

70 The apparatus used may be of iron, steel or any other convenient material. Where the apparatus and materials are, as is desirable, dry there is no necessity of using clay, lead, copper, etc.

75 The operation may be conducted under vacuum, ordinary pressure, or pressure greater than atmosphere, but as a rule ordinary pressure is best. There is no necessity here, as in cracking, of raising the boiling point of the oil by pressure and high "cracking" temperatures are objectionable as unnecessary and as making the action of the aluminum chlorid too quick, violent and uncontrollable. A temperature of about 600° is 80 about as high as is safe even with slow acting nearly exhausted aluminum chlorid. 90 The oil temperature increases progressively as the chlorid loses activity; but generally with gas oil, lubricating oil, still bottoms, etc., the temperature of ebullition will average around 500° F.

100 The double chlorid aluminum and sodium may be employed. As stated, other chlorids, such as ferric chlorid and zinc chlorid may be employed, but their use is not as advantageous as that of aluminum chlorid. The same is true of a number of highly reactive chlorids, such as titanium chlorid, silicon chlorid, phosphorus chlorid, etc. Antimony pentachlorid acts as a chlorinating agent. The trichlorid is not very active. Aluminum chlorid is the best catalyzing agent for the purposes of this invention which I have used.

110 In another and methodical operation, a battery of, say, 8 stills may be provided with connections between them for allowing flow of oil through the series. In the first two stills, crude oil may be distilled, the water and the gasoline and the burning oil fractions naturally present in the crude oil being removed. The heavy oil coming from the second still in series may be led into a third still where it is treated with a small amount of aluminum chlorid, say 2 per cent. Here the easily convertible bodies are converted into gasoline, etc. and removed as vapor. Heavy oil from this No. 3 still may go into No. 4 where it is treated with a slightly larger charge of aluminum chlorid. Most of the aluminum chlorid in No. 3 will 120 125 130

stay in the still and not flow forward with the oil. In No. 4 still a larger proportion of aluminum chlorid may be employed. Heavy oil from this still goes into No. 5 and from 5 No. 5 into Nos. 6, 7 and 8 successively, there being a progressively increasing amount of aluminum chlorid in each successive still. Nos. 7 and 8 stills may for example be operating with as much as 5 per cent of aluminum chlorid, calculated on the amount of 10 oil temporarily in the still. It will be observed that in this manner of operation the oil which is finally converted in No. 8 has been exposed to the influence of aluminum chlorid for the entire time taken in passing to and through Nos. 3, 4, 5, 6 and 7. Here, as in the other alternative described, the operation is such as to give difficultly convertible portions of the oil a long time for 15 conversion. Unlike the prior operation however, the easily convertible portions are treated with only a little aluminum chlorid, comparatively. The aluminum chlorid for each still may be charged therein and the 20 exhausted chlorid removed therefrom in any of the ways previously stated.

Some of the advantages of my invention 25 may be attained by a simple distillation in the presence of aluminum chlorid. If, for 30 example, a charge of crude oil be first distilled in the ordinary way to free it of moisture and to regain the gasoline and kerosene components naturally present, a suitable amount of aluminum chlorid, say 1 to 5 per 35 cent of the amount of oil in the still, may then be added and distillation resumed. A further quantity of gasoline and kerosene of excellent quality will be secured, the amount depending on the activity and 40 amount of the aluminum chlorid and the length of heating. Conversion can be carried as far as may be desired, even to distilling the charge to dryness. For a partial conversion, aluminum chlorid may be 45 used which has been elsewhere employed and has lost part of its activity. As before, the new gasoline and kerosene obtained are of saturated nature, giving little or no reaction with sulfuric acid or iodin. The residual high-boiling material left in the still 50 when such a proportion as may be desired has been converted and distilled, unlike residues from oil-cracking operations, is also of excellent quality and may be used for the 55 manufacture of lubricants, of paraffin, etc. It may be removed from the still, leaving a sludge of aluminum chlorid behind for treatment of another portion of oil, and be treated with strong sulfuric acid. If re- 60 moved from the still in the liquid condition it should not be allowed to become moist or be contacted with aqueous solutions of chemicals prior to the sulfuric acid treatment. Instead of removing the residue from 65 the still it may be steam distilled therein;

or the removed oil may be steam distilled in another still. Where steam distillation is used avoidance of moisture is not important. Steam distillation gives a good quality of oil which may be worked up for lubricants, 70 etc. If the oil is removed and treated with sulfuric acid it may be afterwards washed, neutralized with alkali and boneblacked or treated with fuller's earth.

What I claim is:—

75

1. In the treatment of petroleum oils the process which comprises establishing and maintaining a body of such oil and anhydrous aluminum chlorid at a boiling temperature, removing from the vapors produced the vapors of oils of lower boiling point than that normal to the oil of such body and condensing the removed vapors. 80

2. The process of converting higher boiling petroleum oils into lower boiling oils 85 which comprises heating such a higher boiling oil together with a catalytic chemical of the nature of aluminum chlorid to boiling temperature, separating vapors of lower boiling oil formed from higher boiling oils, 90 and condensing the vapors of the lower boiling oil.

3. The process of converting higher boiling petroleum oils into lower boiling oil 95 which comprises heating such a higher boiling oil together with a catalytic metallic halide to boiling temperature, separating vapors of lower boiling oil formed from higher boiling oil, and condensing the vapors of the lower boiling oil. 100

4. The process of converting higher boiling petroleum oils into lower boiling oil which comprises heating such a higher boiling oil together with a catalytic metallic chlorid to boiling temperature, separating 105 vapors of lower boiling oil formed from higher boiling oil, and condensing the vapors of the lower boiling oil.

5. The process of converting higher boiling petroleum oils into lower boiling oil 110 which comprises heating such a higher boiling oil together with anhydrous aluminum chlorid to boiling temperature, separating vapors of lower boiling oil formed from higher boiling oil, and condensing the 115 vapors of the lower boiling oil.

6. In the treatment of petroleum oils, the process which comprises catalyzing a body of high boiling oil by aluminum chlorid at a boiling temperature while removing vapors 120 of lower boiling products as fast as produced, the vapors prior to removal being cooled sufficient to condense and return volatilized aluminum chlorid.

7. The process of converting higher boiling petroleum oils into lower boiling oil which comprises heating such a higher boiling oil together with anhydrous aluminum chlorid to distillation temperature, separating 125 vapors of lower boiling oil formed from 130

- higher boiling oil, condensing vapors of lower boiling oil formed, and returning the higher boiling oil to the body of oil undergoing distillation.
- 5 8. In the conversion of oils, the process which comprises heating a body of relatively high boiling petroleum oil to about its boiling point in the presence of aluminum chlorid, vapors of low boiling oily bodies being constantly removed and vapors of high boiling bodies being constantly condensed and returned to said body.
- 10 9. In the treatment of petroleum oils, the process which comprises heating an oil for a time, adding anhydrous aluminum chlorid to the hot oil and maintaining the mixture at the boiling point with constant removal of vapors of products of lower boiling point than said oil, such removal being at a temperature sufficiently low to ensure condensation of vapors of high boiling bodies.
- 15 10. In the treatment of petroleum oils, the process which comprises heating an oil for a time, adding anhydrous aluminum chlorid to the oil which has been heated and maintaining the mixture at the boiling point with constant removal of vapors of products of lower boiling point than said oil, such removal being at a temperature sufficiently low to insure condensation of aluminum chlorid vapors.
- 20 11. The process of making low boiling oils from high boiling petroleum oils which comprises heating a mixture of high boiling oil and aluminum chlorid to a temperature at which ebullition and a free development of vapors occur, removing the vapors and cooling the same to a point at which they have a temperature corresponding to the boiling point of the lower boiling oil desired, returning the condensate of higher boiling oils and any aluminum chlorid which may be present to the mixture and condensing the residual vapors of the low boiling oil desired.
- 25 12. The process of converting higher boiling petroleum oils into lower boiling oil which comprises heating such a higher boiling oil together with aluminum chlorid to distillation temperature, separating vapors of lower boiling oil formed from higher boiling oil, condensing vapors of higher boiling oil formed together with aluminum chlorid, and returning the higher boiling oil and the aluminum chlorid to the body of oil undergoing distillation.
- 30 13. The process of converting higher boiling petroleum oils into lower boiling oil which comprises heating such a higher boiling oil together with aluminum chlorid to a distillation temperature and under partial reflux.
- 35 14. The process of converting higher boiling petroleum oils into lower boiling oil which comprises heating a mixture of such a higher boiling oil and aluminum chlorid to distillation temperature, allowing the products of the reaction to pass to a condenser, maintaining the condenser at a temperature not substantially above 350° F., 70 and passing vapors not condensed at this temperature from said condenser to a final condenser for condensation.
- 40 15. The process of converting higher boiling petroleum oils into lower boiling oil which comprises heating a mixture of such a higher boiling oil and aluminum chlorid to distillation temperature, allowing the products of the reaction to pass to a condenser, maintaining the condenser at a temperature not substantially above 350° F., 75 passing vapors not condensed at this temperature from said condenser to a final condenser for condensation and separating and collecting the condensate from the condenser maintained at not substantially above 350° F. 80
- 45 16. In the treatment of petroleum oils, the process which comprises continuously distilling off vapors from a boiling body of hot high boiling oil containing aluminum chlorid, cooling said vapors to a temperature not substantially higher than 350° F. and returning matters condensed in said cooling to said body. 90
- 50 17. The process of producing low boiling oils which comprises heating a body of gas oil to about its boiling point in the presence of aluminum chlorid, cooling the vapors to a temperature not substantially above 350° F., 100 and returning the condensate from such cooled vapors to the body for further treatment and removing the cooled vapors.
- 55 18. In the treatment of petroleum oils, the process which comprises maintaining a body of high boiling oil containing aluminum chlorid at a boiling temperature around 500° F., removing vapors therefrom and cooling said vapors to about 350° F. and returning matters condensed in said cooling to said body. 105
- 60 19. The process of converting higher boiling petroleum oils into lower boiling oil which comprises heating a mixture of such a higher boiling oil and aluminum chlorid to distillation temperature, allowing the vapor products of the reaction to pass to a condenser, maintaining the condenser at a temperature not substantially above 300° F., 115 and passing vapors not condensed at this temperature from said condenser to a final condenser for condensation.
- 65 20. In the conversion of oils, the process which comprises heating to ebullition a body of high boiling oil with aluminum chlorid to a temperature below 600° F., the vapors of catalytically produced lower boiling bodies being removed substantially as fast as such bodies are formed while continuously returning condensed vapors of 120
- 70 130

higher boiling bodies and of aluminum chlorid.

21. In the conversion of oils, the process which comprises heating a body of high boiling oil with aluminum chloride to a temperature of about 500° F., to produce ebullition, the vapors of catalytically produced lower boiling bodies being removed substantially as fast as such bodies are formed 10 while continuously returning condensed vapors of higher boiling bodies and of aluminum chlorid.

22. The process of converting higher boiling petroleum oils into lower boiling oil 15 which comprises heating a mixture of such a higher boiling oil and aluminum chlorid to a temperature not substantially above 600° F., while removing and condensing vapors of lower boiling oil formed thereby.

23. The process of converting higher boiling petroleum oils into lower boiling oil which comprises heating a mixture of such a higher boiling oil and aluminum chlorid to temperatures not substantially above 600° 25 F. and during such heating condensing and separately collecting the lower boiling oils produced thereby.

24. The process of converting gas oil or fuel oil into lower boiling oil which comprises heating the gas oil or fuel oil together with aluminum chlorid to temperatures around 500-550° F., while removing and condensing vapors of lower boiling oil formed thereby.

25. The process of converting gas oil or fuel oil into lower boiling oil which comprises heating the gas oil or fuel oil together with aluminum chlorid to temperatures around 500-550° F. and during such heating 40 separately condensing and collecting the lower boiling oil produced thereby.

26. The process of producing kerosene and gasoline from petroleum oils having boiling points higher than either which comprises 45 heating such a higher boiling point oil in the presence of aluminum chlorid to distillation temperature, and during such heating condensing the vapors of kerosene and gasoline produced thereby.

27. The process of producing kerosene and gasoline from petroleum oils having boiling points higher than either which comprises heating such a higher boiling point oil in the presence of aluminum chlorid to 55 distillation temperature, and during such heating together condensing the vapors of kerosene and gasoline produced thereby, and then separating the gasoline and kerosene.

28. In the distillation of petroleum oils 60 with aluminum chlorid, the process which comprises establishing and maintaining a body of such oil and of aluminum chlorid at distilling temperature and supplying hot oil to such body.

29. In the treatment of petroleum oils, the

process which comprises continuously distilling off low boiling vapors from a boiling body of high boiling oil containing aluminum chlorid and continuously supplying additional high boiling oil to said body.

30. In the treatment of petroleum oils, the process which comprises heating to ebullition a body of relatively high boiling oil with aluminum chlorid with constant removal of vapors of relatively lower boiling 75 oils produced by the catalytic action of said chlorid in said body, the volume of said body being kept substantially constant during said heating operation by additions of high boiling oil in amounts corresponding 80 to the amounts of low boiling products removed.

31. The process of converting high boiling petroleum oils into lower boiling oil which comprises heating such a higher boiling oil together with aluminum chlorid to distillation temperature, separating vapors of lower boiling oil formed from higher boiling oil, condensing the lower boiling oil and adding oil and aluminum chlorid to the body 85 undergoing distillation.

32. In the continuous conversion of higher boiling petroleum oils into lower boiling oils, the process which comprises establishing and maintaining a boiling body of such 95 higher boiling oil in the presence of aluminum chlorid while constantly removing vapors of lower boiling oils produced by the action of such aluminum chlorid, the volume of said body being maintained substantially constant by additions of higher boiling oil during the operation and exhausted aluminum chlorid being removed from such oil from time to time and replaced by additions of active aluminum chlorid.

33. The process of converting higher boiling petroleum oils into lower boiling oils which comprises heating such a higher boiling oil together with aluminum chlorid to 100 distillation temperature, separating vapors of lower boiling oil formed from higher boiling oil, condensing the lower boiling oil and adding high boiling oil and aluminum chlorid admixed therewith to the body of oil undergoing distillation.

34. The process of converting higher boiling petroleum oils into lower boiling oils which comprises heating such a higher boiling oil together with aluminum chlorid to 110 distillation temperature, separating vapors of lower boiling oil formed from higher boiling oil, condensing the lower boiling oil and adding hot high boiling oil and aluminum chlorid to the body undergoing distillation.

35. The process of converting higher boiling petroleum oils into lower boiling oils which comprises heating such a higher boiling oil together with aluminum chlorid to 120 distillation temperature, separating vapors of lower boiling oil formed from higher boiling oil, condensing the lower boiling oil and adding hot high boiling oil and aluminum chlorid to the body undergoing distillation.

- of lower boiling oil formed higher boiling oil, condensing the lower boiling oil and adding hot oil and aluminum chlorid admixed therewith to the body of oil undergoing distillation.
36. In the conversion of oils, the process which comprises continuously distilling a continuously replenished body of petroleum oil in the presence of about 5 per cent of active aluminum chlorid till said aluminum chlorid passes into a coky matter, said coky matter being removed from the oil when its activity lessens and replaced with active aluminum chlorid.
- 10 37. The process of converting higher boiling petroleum oils into lower boiling oils which comprises heating such a higher boiling oil together with aluminum chlorid to distillation temperature, separating vapors of lower boiling oil formed from higher boiling oil, condensing the lower boiling oil and adding vapors of aluminum chlorid to the body undergoing distillation.
- 15 38. The process of converting higher boiling petroleum oils into lower boiling oils which comprises distilling such a higher boiling oil in admixture with aluminum chlorid, condensing the lower boiling oil produced and during distillation withdrawing residual aluminum chlorid from the body of higher boiling oil.
- 20 39. The process of converting higher boiling petroleum oils into lower boiling oils which comprises admixing such a higher boiling oil with partially spent aluminum chlorid which has been used in previous treatment of oils, heating to a distillation temperature, and condensing the lower boiling oil produced.
- 25 40. The process of converting higher boiling petroleum oils into lower boiling oils which comprises distilling such a higher boiling oil in the presence of aluminum chlorid, during the distillation, collecting and condensing vapors of lower boiling oil produced, and then gradually raising the temperature of the higher boiling oil and the aluminum chlorid undergoing distillation as the lower boiling oil is condensed.
- 30 41. In the conversion of high boiling oils, the process which comprises heating a charge of aluminum chlorid in contact with a constant volume of oil for a period of not less than 48 hours, the low boiling products produced in such heating being removed substantially as fast as formed and the constant volume of oil being preserved by additions of new oil.
- 35 42. The process of converting higher boiling petroleum oils into lower boiling oils which comprises heating such a higher boiling oil together with aluminum chlorid to distillation temperature, separating vapors of lower boiling oil formed from higher boiling oil, condensing vapors of lower boil-
- ing oil formed, and agitating the mixture of higher boiling oil and aluminum chlorid undergoing distillation.
43. In the conversion of oils, the process which comprises boiling a body of oil in the presence of aluminum chlorid under continuous agitation, the volume of such oil being kept replenished by additions of high boiling oil to compensate for volatilized oils.
- 75 44. In the conversion of oils, the process which comprises heating a constantly replenished boiling body of such oil with a charge of aluminum chlorid with constant agitation until the aluminum chlorid loses its high activity and tends to settle out as a coky mass.
45. The process of converting higher boiling petroleum oils into lower boiling oils which comprises heating such a higher boiling oil together with from 1 to 5 per cent of aluminum chlorid to distillation temperature, separating vapors of lower boiling oil formed from higher boiling oil, condensing vapors of lower boiling oil formed, and agitating the mixture of higher boiling oil and aluminum chlorid undergoing distillation.
- 80 46. The process of converting higher boiling petroleum oils into lower boiling oils which comprises heating such a higher boiling oil together with about 5 per cent of aluminum chlorid to distillation temperature, separating vapors of lower boiling oil formed from higher boiling oil, condensing vapors of lower boiling oil formed, and agitating the mixture of higher boiling oil and aluminum chlorid undergoing distillation.
- 85 47. The process of converting higher boiling petroleum oils into lower boiling oils which comprises drying such a higher boiling oil, admixing the dried higher boiling oil with aluminum chlorid and heating to distillation temperature, and condensing vapors of lower boiling oil formed.
- 90 48. The process of converting higher boiling petroleum oils into lower boiling oils which comprises distilling such a higher boiling oil to remove any water and the lower boiling hydrocarbons naturally present, adding aluminum chlorid after such removal of lower boiling hydrocarbons, heating to distillation temperature, and condensing the new lower boiling oil produced.
- 95 49. The process of converting higher boiling petroleum oils of the nature of fuel oil or gas oil into lower boiling oils which comprises heating such fuel oil or gas oil to distillation temperature with aluminum chlorid and as distillation proceeds condensing the lower boiling oil produced by such heating.
- 100 50. The process of producing gasoline from higher boiling petroleum oils which comprises distilling such a higher boiling oil in the presence of aluminum chlorid and
- 105 110 115 120 125 130

during the distillation condensing the gasoline vapors produced thereby.

51. The process of converting higher boiling petroleum oils into lower boiling oils which comprises heating such a higher boiling oil in admixture with aluminum chlorid to distillation temperature, condensing the lower boiling oil produced, removing the aluminum chlorid from the said mixture, and treating additional higher boiling petroleum oil with said removed aluminum chlorid at a distillation temperature.

52. The process of converting higher boiling petroleum oils containing sulfur into lower boiling oils which comprises distilling such a higher boiling oil in the presence of aluminum chlorid and during the distillation condensing the lower boiling oil formed thereby.

53. The process of converting higher boiling petroleum oils containing sulfur into lower boiling oils which comprises treating such a higher boiling oil with sulfuric acid to remove the sulfur and to dry it, heating the sulfur-free and dry products of such treatment with aluminum chlorid to distillation temperature, and collecting and condensing the lower boiling oil produced.

54. In the conversion of sulfur-containing petroleum oils into lower boiling oils, the process which comprises removing sulfur from such an oil and then boiling said oil as a constant-volume body in the presence of aluminum chlorid, the vapors of lower boiling oils being continuously removed and the volume being replenished with fresh treated oil.

55. The process of producing lower boiling petroleum oils from higher boiling oils which comprises distilling such a higher boiling oil in the presence of aluminum chlorid in a still, collecting the vapors of lower boiling oils produced, passing the higher boiling oils to a second still, distilling such higher boiling oils therein with aluminum chlorid and collecting from said second still the lower boiling oil produced.

56. The process of converting higher boiling petroleum oils into lower boiling oils which comprises distilling the same in the presence of aluminum chlorid in a still, condensing the vapors of lower boiling oils produced, passing the higher boiling oils to another still and distilling the same therein with a larger percentage of aluminum chlorid than was used in the first distillation, and collecting the vapors of lower boiling oils produced in the second distillation.

57. The process of converting higher boiling petroleum oils into lower boiling oils which comprises passing such a higher boiling oil in admixture with aluminum chlorid through a plurality of stills, distilling the mixture in each such still, and collecting the lower boiling oil produced in each such still.

58. The process of converting higher boiling petroleum oils into lower boiling oils in a plurality of stages, which comprises heating such oils in the presence of aluminum chlorid in each such stage to distillation temperature, collecting the vapors of lower boiling oils produced from each such stage and passing higher boiling oils from a preceding stage to a succeeding stage.

59. The process of converting higher boiling petroleum oils into lower boiling oils in a plurality of stages which comprises heating such a higher boiling oil in the presence of aluminum chlorid in each such stage to distillation temperature, collecting the vapors of lower boiling oil produced from each such stage and passing higher boiling oils together with some aluminum chlorid admixed with the oil to a succeeding stage, but leaving settled aluminum chlorid in admixture with the oil in the preceding stage.

60. The process of converting petroleum hydrocarbons having higher-boiling points into naphtha, which consists in heating a mixture of said hydrocarbons and anhydrous aluminum chlorid to a temperature producing vapor of a lower boiling oil having an end-boiling point not substantially above the end-boiling point of naphtha and maintaining the mixture at such temperature.

61. The process of converting petroleum hydrocarbons having higher-boiling points into oils having lower-boiling points, which consists in heating a mixture of said hydrocarbons and anhydrous aluminum chlorid to a temperature producing vapor of a lower boiling oil having an end-boiling point not substantially above the end-boiling point of illuminating oil and maintaining the mixture at such temperature.

62. The process of converting petroleum hydrocarbons having higher-boiling points into naphtha, which consists in heating a mixture of said hydrocarbons and anhydrous aluminum chlorid to a temperature producing vapor of a lower boiling oil having an end-boiling point not substantially above the end-boiling point of naphtha and maintaining the mixture at such temperature until the greater part of the oil has been converted into naphtha.

63. The process of converting petroleum hydrocarbons having higher-boiling points into oils having lower-boiling points, which consists in heating a mixture of said hydrocarbons and anhydrous aluminum chlorid to a temperature producing vapor of lower-boiling oil having an end-boiling point not substantially above the end-boiling point of illuminating oil and maintaining the mixture at such temperature until the greater part of the oil has been converted into naphtha and illuminating oil.

64. The process of converting petroleum hydrocarbons having higher-boiling points

into oils having lower-boiling points, which consists in heating a mixture of such hydrocarbons and anhydrous aluminum chlorid to a temperature producing vapor of lower-boiling oil having an end-boiling point above the end-boiling point of naphtha, but below the end-boiling point of illuminating oil, maintaining the mixture at such temperature, condensing oils of the character of illuminating oil driven off in a preliminary cooling chamber, and conducting the naphtha driven off to a condenser.

65. The process of converting petroleum hydrocarbons having higher-boiling points into naphtha, which consists in heating a mixture of said hydrocarbons and anhydrous aluminum chlorid to a temperature producing vapor of lower boiling oil having an end-boiling point above the end-boiling point of naphtha, but below the end-boiling point of illuminating oil, condensing oil of the character of illuminating oil driven off in a preliminary cooling chamber, returning said oil to the still to be further acted on where-
20 by higher-boiling oil is converted into naphtha and conducting the naphtha driven off to a condenser.

66. The process of converting petroleum hydrocarbons having higher-boiling points into oils having lower-boiling points, which consists in heating a mixture of such hydrocarbons and anhydrous aluminum chlorid to a temperature producing vapor of lower boiling oil having an end-boiling point above the end-boiling point of naphtha, but below the end-boiling point of illuminating oil, maintaining the mixture at such temperature until the greater part of the oil has been converted into naphtha and illuminating oil, condensing oil of the character of illuminating oil driven off in a preliminary cooling chamber, and conducting the naphtha driven off to a condenser.

67. The process of converting petroleum hydrocarbons having higher-boiling points into naphtha, which consists in heating a mixture of said hydrocarbons and anhydrous aluminum chlorid to a temperature producing vapor of lower boiling oil having an end-boiling point above the end-boiling point of naphtha but below the end-boiling point of illuminating oil, condensing oils of the character of illuminating oil driven off in a preliminary cooling chamber, returning said oils to the still to be further acted on, whereby the greater portion of the higher-boiling oil is converted into naphtha, and conducting the naphtha driven off to a condenser.

68. The process of converting higher boil-

ing petroleum oils into lower boiling oils with the aid of aluminum chlorid which comprises heating the higher boiling oil in the presence of aluminum chlorid to a temperature higher than the end boiling point 65 of the lower boiling oil desired, and while heating removing and condensing vapors of the lower boiling oil produced thereby.

69. The process of converting higher boiling petroleum oils into lower boiling oils 70 with the aid of aluminum chlorid which comprises heating such a higher boiling oil in the presence of aluminum chlorid to a temperature higher than the end boiling point of the lower boiling oil desired, but 75 not substantially higher than the end boiling point of the higher boiling oil operated upon, and removing and condensing vapors of the lower boiling oil produced.

70. The process of converting higher boiling petroleum oil into gasoline with the aid of aluminum chlorid which comprises heating a mixture of such a higher boiling oil and aluminum chlorid to a temperature above the end-boiling point of gasoline, 85 and while heating collecting and condensing the vapors of gasoline produced thereby.

71. A process of converting petroleum oils of relatively high boiling points into products of lower boiling points which comprises 90 treating said oils with a catalyst comprising the hydrocarbon addition products of a halogen aluminum compound.

72. A process which comprises heating petroleum hydrocarbon materials of relatively 95 high boiling points with a hydrocarbon derivative of an aluminum halid compound, and distilling off products of lower boiling point than the starting material.

73. In the process of treating petroleum 100 hydrocarbon oil with a catalyst comprising a halogen aluminum hydrocarbon addition product the step of allowing an inflow of fresh material in order to make the process continuous.

74. In the treating of mineral oils or their distillates with a catalyst the step of increasing the rate of reaction which comprises subjecting said materials during the contact of the same with the catalyst to the 110 action of chemical and physical agents, capable of increasing the rate of the catalytic reaction.

In testimony whereof, I affix my signature in the presence of two subscribing witnesses. 115
